CHARLES L. REESE, OF WILMINGTON, DELAWARE, ASSIGNOR TO E. I. DU PONT DE NEMOURS & COMPANY, OF WILMINGTON, DELAWARE, A CORPORATION OF DELAWARE.

PROCESS OF FORMING BURSTING CHARGES.

1,307,599.

Specification of Letters Patent. Patented June 24, 1919.

Application filed August 17, 1918. Serial No. 250,336.

To all whom it may concern:

Be it known that I, CHARLES L. REESE, of Wilmington, in the county of New Castle, and in the State of Delaware, have invented 5 a certain new and useful Improvement in Processes of Forming Bursting Charges; and do hereby declare that the following is a full, clear, and exact description thereof.

This invention relates to processes of 10 forming bursting charges for containers intended to be exploded, such as shells, grenades, torpedoes, mines, etc.

The object of the invention is to provide a process of forming such a bursting charge 15 which shall have, among others, the advantages of rendering available new sources of raw materials; of providing materials capable of being used for the purpose, either by themselves or with others; and of providing 20 a process by which said mixtures can be cast into shells or other containers intended to be exploded, and there caused to solidify and completely fill the space provided for the charge.

25 In the accompanying drawing,

The figure is an axial section of a shell containing a bursting charge embodying my invention.

The invention is capable of being carried 30 out in many different ways, but for the purpose of illustration only one form of the invention will be described herein.

In filling with bursting charges containers intended to be exploded, such as shells, 35 grenades, torpedoes, mines, etc., it is desirable to introduce the largest possible charge into a given space, so as to produce the maximum possible bursting effect. Trinitrotoluol has heretofore been used to a 40 very large extent, because, among other reasons, it has a relatively low melting point and is, therefore, easily melted; it can be kept melted while being introduced into the shell or other body, and it does not freeze.

45 or solidify until it has reached the final condition in which it is to remain. The supply of trinitrotoluol, however, may not be adequate, and it is very desirable to render other materials available to replace the 50 trinitrotoluol wholly or in part.

I have discovered a new bursting charge for the said purpose, which is of high power, and which may consist wholly of a new substance, or of such substance combined with

other explosives. While the said substance 55 is useful and valuable when introduced into the shell or other container in solid condition, its melting point is too high to permit it, as a practical manner, to be melted and cast into the shell. I have, therefore, invented a process by which the said substance can, in effect, become part of a molten mass of such low melting point as to be capable of being successfully cast into the shell.

The new substance to which I refer is produced by the nitration of aromatic hydrocarbons of the benzene series, having a higher boiling point than toluene, and, in particular, by the nitration of xylene. The nitration is accomplished by the use of 60 strong nitric and sulfuric acid, and the action is preferably so controlled as to produce a solid, finely-divided product. I find that when starting with xylene I am able to prepare a solid nitroxylene, which approximates trinitroxylene in composition. This product can be detonated by ordinary commercial detonators, and has an explosive force nearly equal to that of trinitrotoluol.

In charging a shell, the nitroxylene may 65 be pressed into the shell in a dry condition, making a compact charge which is readily detonated by the usual primer, or it may be mixed with another nitro compound, such for example as trinitrotoluol.

In order to get the effect of completely casting the shell or other container full of the explosive, I mix the said aromatic nitro bodies made from the aromatic hydrocarbons having boiling points higher than 70 toluol with more easily fusible nitro bodies, such as trinitrotoluol, and cast the mixture together into the shell. For example, a mixture of approximately 40% nitroxylene and 60% trinitrotoluol can be thus cast. Desirable proportions are 50 to 70 parts of trinitrotoluol and 50 to 30 parts of nitroxylene.

In the figure of the accompanying drawing, I have shown more or less diagrammatically, a shell body 1, having within it a bursting charge 2, such as I have described, and having a fuse 3 containing a detonator for detonating the bursting charge 2.

By thus mixing and casting the charges, it 105 is not necessary to use temperatures greatly above those of the more easily fusible nitro bodies, and yet substantially the same effect

is obtained as if the more difficultly fusible nitro bodies were melted and cast into the shell or other container, if that were feasible.

The trinitrotoluol used may be either a 5 crude product, such as obtained by direct nitration of toluol, or a product obtained by refining the crude product. The mixture is prepared for casting by melting the trinitrotoluol and to this melted product adding 10 solid trinitroxytol, keeping the temperature of the mixture well above the melting point of the trinitrotoluol. Thorough mixing of the two explosives can be carried out by any suitable method of mechanical agitation, or 15 simply by stirring with a paddle by hand. Only a very small proportion of the trinitroxytol is soluble in or melted by the trinitrotoluol.

It is not necessary that the mixture produce 20 a homogeneous liquid product, but the trinitroxytol can be added in very appreciable amounts until the mixture carries a maximum percentage of trinitroxytol in suspension. The maximum percentage that 25 can be added in suspension is determined by whether the mixture can be poured. Such a mixture is, as stated, represented by one carrying 60% of triton and 40% of trinitroxytol, such a mixture pouring nicely at about 30 80° C. Higher percentages of trinitroxytol can be used, especially if higher temperatures are employed, and lower percentages of trinitroxytol, of course, can be used satisfactorily. I prefer, however, the 60-40 35 mixture, inasmuch as it produces a mixture that can be easily poured and gives a casting of excellent physical and explosive properties.

This invention thus makes it possible as 40 completely to fill a shell with a charge consisting partly of the more difficultly fusible nitro bodies as it has heretofore been possible to fill them with the more easily fusible nitro bodies, and in particular furnishes substitutes for trinitrotoluol by which bursting charges can be produced that are substantially as effective as if they consisted entirely of trinitrotoluol.

By the term "container," as used in the 50 claims, is meant a container intended to be exploded, such as a shell, grenade, torpedo, mine, etc.

I claim:

1. The process which comprises charging 55 an explosive container with a difficultly fusible nitro body by mixing it with an easily fusible nitro body, and pouring the mixture into the container while the latter nitro body is in a molten condition.

60 2. The process which comprises charging

an explosive container with a nitrated hydrocarbon of the benzene series having a melting point higher than that of trinitrotoluol by mixing the first-mentioned substance with a lower melting nitrated hydrocarbon while molten, and pouring the mixture into a container. 65

3. The process which comprises charging an explosive container with a nitrated hydrocarbon of the benzene series having a 70 melting point higher than that of trinitrotoluol by mixing the first-mentioned substance with molten trinitrotoluol, and pouring the mixture into a container.

4. The process which comprises charging 75 an explosive container with a nitrated xylene by mixing it with an easily fusible nitro body, and pouring the mixture into the container while the latter nitro body is in a molten condition. 80

5. The process which comprises charging an explosive container with a nitrated xylene having a melting point higher than that of trinitrotoluol by mixing the first-mentioned substance with a lower melting nitrated hydrocarbon while molten, and pouring the mixture into a container. 85

6. The process which comprises charging an explosive container with a nitrated xylene having a melting point higher than that of trinitrotoluol by mixing the first-mentioned substance with molten trinitrotoluol, and pouring the mixture into a container. 90

7. The process which comprises charging an explosive container with a solid nitrated 95 xylene by mixing it with an easily fusible nitro body, and pouring the mixture into the container while the latter nitro body is in a molten condition.

8. The process which comprises charging 100 an explosive container with a solid nitrated xylene having a melting point higher than that of trinitrotoluol by mixing the first-mentioned substance with a lower melting nitrated hydrocarbon while molten, and 105 pouring the mixture into a container.

9. The process which comprises charging an explosive container with a solid nitrated xylene having a melting point higher than that of trinitrotoluol by mixing the first- 110 mentioned substance with molten trinitrotoluol, and pouring the mixture into a container.

In testimony that I claim the foregoing I have hereunto set my hand.

CHARLES L. REESE.
